HAIRCUTTING DEVICE

Filed Aug. 5, 1969

FIG. 1

FIG. 2

FIG. 3

FIG. 4

FIG. 5

INVENTOR
ARNOLD W. LUNDELL

The operation of the device is clearly seen in FIG. 4 in which two possible positions of the device are shown. In this regard, it should be apparent that the full line position of the blade 54 shows the same in operative position as a haircutting and trimming device. In the dotted line position thereof, the blade 54 is lowered to a position in which the same is suitable for use in straight razor shaving.

The fixed blade holder part 12 of the device is provided with indicator markings 56 that are aligned with adjacent and corresponding markings 58 on the movable blade holder part 14. This arrangement permits the setting and resetting of a selected depth of cut of the blade 54 in the housing 10.

As seen in FIG. 5, the small inclined surface 51 results in a starting ramp for inserting the forward edge of blade 54 in the blade housing 10, and the large inclined surface 53 is a larger ramp for continuing the guiding of the partially inserted blade 54 in said housing.

As seen in FIG. 3, the blade holder 12 is provided with a bearing surface 37 that engages and abuts co-acting bearing surface 39 of the blade holder part 14. Thus, the bearing surfaces result in the movable blade part 14 being guided for movement in a positive manner in the blade housing 10, and the springs 50 function to bias or urge the movable blade holder part 14 against the front surface of the blade 54, thereby firmly holding the latter in the blade housing.

I claim:

1. A haircutting device comprising a blade housing including a first blade holder part having a comb and provided with an extension having a finger rest at one end thereof, a handle pivoted to said extension whereby in one position thereof the finger rest is inaccessible and in another position thereof the finger rest is accessible, a second blade holder part interfitting with said first blade holder part but having a longitudinal through-passage, an elongated gear in said first blade holder part and at least one rack on said second blade holder part engaging said gear, a cutter blade inserted between said first and second blade holder parts and means holding said cutter blade therein for movement relative to said comb, said means including a pair of side grooves in said first blade holder part, a second blade holder part having a pair of relative flat springs with free ends which are adapted to be inserted in said side grooves whereby said second blade holder part is urged into engagement with said blade, said cutter blade being replaced by another cutter blade by butting said other cutter in an end-to-end manner with the said blade to be discarded and pushing the latter

50

through said through-passage and a finger-operable control wheel located in said extension for rotating said gear and thereby moving said blade in a selected direction.

2. A haircutting device comprising a blade housing including a first blade holder part having a comb and provided with an extension, a handle secured to said extension, a second blade holder part interfitting with said first blade holder part but having a longitudinal through-passage, a single edge cutter blade inserted between said first and second blade holder parts and releasably held therein for movement relative to said comb, a ramp-like inclined surface at one entrance of said longitudinal through-passage for guiding said cutter blade between said first and second blade holder parts, said first and second blade holder parts having adjacent upper stop members for said cutter blade, said comb and an adjacent part of said second blade holder part having lower stop members for said cutter blade, an elongated gear in said first blade holder part and at least one rack on said second blade holder part engaging said gear, and a finger-operable control device located in said extension for rotating said gear and thereby moving said blade in a selected direction.

3. A haircutting device as claimed in claim 2 wherein said blade has a thickened spine for engaging said upper stop members and said lower stop members on said first and second blade holder parts.

4. A haircutting device as claimed in claim 2 wherein two spaced racks are provided on said second blade holder part, a pair of complementary tracks in said first blade holder part in which said racks are movable therein by said elongated gear.

5. A haircutting device as claimed in claim 2 further comprising co-acting indicator means on said first and second blade holder parts for marking the preselected depth of cut of said blade in said blade housing.

6. A haircutting device as claimed in claim 2 wherein said first and second blade holder parts are provided with complementary sections that index said first and second blade holder parts for positive movement relative to each other.
